UNITED STATES PATENT OFFICE.

LUCIEN VIALET-CHABRAND, OF LA CIOTAT, FRANCE.

ACETYLENE LIGHTING APPARATUS.

1,411,141.

Specification of Letters Patent. Patented Mar. 28, 1922.

Application filed May 1, 1919. Serial No. 293,990.

To all whom it may concern:

Be it known that I, LUCIEN VIALET-CHABRAND, a citizen of the Republic of France, residing at La Ciotat, Bouches-du-Rhone 5 Department, in the Republic of France, have invented certain new and useful Improvements in Acetylene Lighting Apparatus, of which the following is a specification.

10 The present invention has for its object an apparatus which has received the name of "Aquatic torch" because it can only act in water.

15 A form of construction thereof is shown in the appended drawing by way of example.

Fig. 1 is a an axial vertical section of the apparatus.

Fig. 2 is an elevation thereof.

20 Fig. 3 is a plan of a phosphide of calcium basket.

Fig. 4 is a vertical section of said basket.

This apparatus comprises three distinct 25 chambers 1, 2 and 3; the chamber 1 containing carbide of calcium, 2 phosphide of calcium, and 3 which is watertight serving to float the apparatus.

The charge of carbide, which is the heaviest, serves to produce, the acetylene 30 gas which rises through a tube 4 and passes through one or more orifices 5 of a tube 6, the water reaches the carbide through a tube 7 and its lateral orifices. The water ascends to the phosphide through the orifice 9 of a 35 tube 8, the phosphuretted hydrogen gas escapes from the receptacle 2 through the orifice 10 and produces a flame which ignites spontaneously on contact with air. The phosphide therefore produces the ignition 40 of the jet of acetylene and the weights of the two substances are in proportion with the duration of lighting which it is desired to obtain.

45 It is to be noted that in the apparatus the two substances are acted on separately and that the acetylene gas is intentionally produced at a much greater pressure than that of the phosphorated hydrogen gas, for the purpose of obtaining an elongated and very 50 luminous flame. The water reaches the carbide by rising in the tube 7 through its lower orifice 11 and passing out laterally through its lateral orifices.

55 The operation which has just been described, takes place when the apparatus is

immersed in the water and the upper orifices 5 and 10 together with the lower ones 9 and 11 are free, but it must be noted that when the apparatus is not in use the four orifices are covered by two soldered strips 60 12 and 13 which are successively removed by hand or automatically only at the moment of using the apparatus. These strips are carefully soldered at their edges and also transversely, but just sufficiently to 65 cover the orifices to be screened and so as to be removable by application of sufficient force. Claws 14 with pins 15 fix the ends of said strips with a view to preventing their removal by a too slight effort resulting from 70 a wrong operation. The free ends of said strips are provided with rings 16 and 17. The torch also carries a collar 18 provided with a ring 19. This latter ring serves to 75 suspend the torch and further to connect it by means of a cable 19^a, which may be 4 to 5 metres long, to the salvage device which it is to illuminate.

To the rings 16 and 17 are secured the 80 ends of two cables 16' and 17' of unequal lengths, the other ends of which are attached to a suitable point of the ship. The salvage device and the torch being hooked together on board, it is understood that at the moment when both are thrown into the 85 water the salvage device, after a sufficient fall, strains the cord which connects it to the torch and draws the latter after it while tearing off in succession the two strips 12 and 13 by means of the two ropes which 90 connect them on board, this succession of removals results from the fact that the shorter rope is first stretched and that it is only after the removal of the corresponding strip that the rope attached to the second strip is strained, which strip is then removed in its turn.

In the preceding description it has been described that the water reaches the carbide through the interior of the tube 7 and the 100 phosphide through the end of the tube 8. The tube 7 is provided with holes so that the carbide cannot penetrate therein to obstruct it. In proportion to the decomposition of the carbide starting from the bottom, the 105 water rises in the tube 7 in order to flow out over the upper parts and continue the operation, which would not take place if the water penetrated simply through the orifice 11 which the carbide would obstruct at the 110

end of a certain time, especially when the apparatus contains a considerable weight of carbide. The tube 7 therefore constitutes a rising column always free and its employment is of great practical importance, as is also the partitioning of the carbide by perforated disks 20 between which this substance is placed in order to prevent the accumulation and consequently over-production of gas during working.

In the receptacle 2 the phosphide is also divided into sections in order to avoid the accumulation and over-production during wetting; the tube 8 ends in a free chamber 15 21 from which the water rises in the perforated tube 22 which always provides a free passage; the water flows out through the lateral orifices of said tube 22 and acts on the phosphide of calcium which is placed in 20 a series of baskets 23, 24, 25, 26, with perforated walls arranged one below another.

The lowest basket 23 is smaller than the others and the load which it contains is intended to supply very rapidly a suitable 25 amount of phosphorated hydrogen as soon as the water arrives from the tube 8 and the chamber 21 into the bottom of the receptacle 2, in order to ensure the immediate lighting of the acetylene.

30 27 designates partitions fixed in the basket 23 to support the basket placed above.

28 designates a counterweight secured to the bottom of the receptacle 1 and serving as ballast.

35 Claims:

1. In a floating acetylene lighting apparatus, the combination of a calcium carbide container, a calcium phosphide container situated above the former, floating 40 means surrounding the second container two water inlet passages starting from the bottom of the first container, one of which passes through the first container, the second of which is perforated and extends into 45 the first container, the second passage being concentric to the first.

2. In a floating acetylene lighting apparatus, the combination of a calcium carbide container, a calcium phosphide container, floating means, water inlet passages, 50 two perforated tubes disposed respectively at the centers of these two containers, and perforated disks surrounding the said tubes to prevent the caking or settling of the calcium carbide and the calcium phosphide.

55 3. An acetylene lighting apparatus com-

prising a carbide of calcium receptacle, a phosphide of calcium receptacle fixed above the former; floating means round the second receptacle, a water inlet-pipe starting from 60 the bottom of the first receptacle and extending inside the latter, a water inlet pipe passing through the first named pipe, issuing at the bottom in the centre of the orifice of said first pipe and extending upwards into 65 the bottom of the said phosphide of calcium receptacle an acetylene outlet pipe extending from the top of the first receptacle to the top of the second receptacle, and a phosphorated hydrogen outlet orifice in the top of 70 the second receptacle beside the orifice of the said acetylene outlet pipe.

4. An acetylene lighting apparatus comprising a carbide of calcium receptacle, a phosphide of calcium receptacle fixed above 75 the former, a water inlet-pipe starting from the bottom of the first receptacle, a water inlet-pipe passing through the first named pipe to feed the said upper phosphide of calcium receptacle, a gas outlet-pipe extending upwards from the top of the first receptacle, a gas outlet-orifice in the top of the second receptacle near the orifice of the said outlet pipe, two perforated tubes placed at the centre of the two receptacles respectively, 80 and perforated annular partitions around the said tubes to divide the mass of carbide of phosphide of calcium respectively.

5. In a floating acetylene lighting apparatus, a receptacle for calcium phosphide, a 90 float surrounding said receptacle and extending to the bottom of the latter, a receptacle for calcium carbide extending down from the bottom of said float and having a water inlet, an acetylene gas-tube extending 95 from the carbide receptacle to the top of the phosphide receptacle and having an outlet above the phosphide receptacle, the latter having a gas outlet at its top and a water inlet at its bottom, said float being of relatively great horizontal extent so that it normally retains the greater part of the phosphide container above the level of water on which the float rides.

In testimony, that I claim the foregoing 105 as my invention I have signed my name in presence of two subscribing witnesses.

LUCIEN VIALET-CHABRAND.
